US0D1102573S

(12) **United States Design Patent** (10) **Patent No.:** **US D1,102,573 S**
(45) **Date of Patent:** **** Nov. 18, 2025**

(54) **NECK FAN**

(71) Applicant: **Shenzhen Tianman Technology Co., Ltd.**, Shenzhen (CN)

(72) Inventor: **Yanan Du**, Shenzhen (CN)

(73) Assignee: **Shenzhen Tianman Technology Co., Ltd.**, Shenzhen (CN)

(**) Term: **15 Years**

(21) Appl. No.: **29/983,468**

(22) Filed: **Jan. 10, 2025**

(51) LOC (15) Cl. **23-04**

(52) U.S. Cl.

USPC **D23/370**

(58) **Field of Classification Search**

USPC D8/61, 29.1; D23/382, 370, 499, 383, D23/352

(57) **CLAIM**

The ornamental design for a neck fan, as shown and described.

DESCRIPTION

FIG. 1 is a front perspective view of a neck fan, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the neck fan, which form no part of the claimed design.

1 Claim, 8 Drawing Sheets
